BOTTLE CAP

Jean R. L. Martin, New York, N. Y., assignor to
 Coty, Inc., Wilmington, Del., a corporation of
 Delaware

Application January 10, 1950, Serial No. 137,721

4 Claims. (Cl. 215—43)

1

This application relates to bottle caps or sealing devices. The application is a continuation in part of my prior application, Serial No. 83,585 filed March 26, 1949, now Patent No. 2,526,622.

In my prior application, I described a sealing member in the form of a plug or stopper which served the consumer throughout the life of a bottle of perfume or other fluid. That is, after removal of the cap, the user removed and then reapplied the plug during each use of the perfume. The plug effectively prevented the leaking of fluid from the container by means of the specific construction thereof.

According to the present invention, a device has been provided wherein a plug resembling the plug of my prior application is incorporated in the cap of the bottle so that its removal or application does not require a separate operation. Thus, the removal of the cap automatically removes the stopper, and application of the cap automatically applies the stopper to the bottle. Because of the unique construction of the stopper, and by virtue of the general association of the two elements, many and unexpected advantages accrue. For example, a common difficulty and complaint among producers of perfume was the fact that a screw threaded cap often loosened in transit causing fluid leakage. Elaborate external means have often been used to maintain the cap against such accidental displacement. However, such means are eliminated in accordance with the instant invention because the plug or stopper itself functions as an anchoring device for the cap until a positive force, as by the user of the article, is applied so as to unscrew the cap. Such unscrewing is effected against the normal anchoring action of the plug as will be hereinafter made clear.

It is further evident that the incorporation of the plug and cap, by the means which will be hereinafter described and by virtue of the specific materials from which the elements are fabricated, simplifies the operations required of the consumer in that one is not even made aware of the fact that a plug is applied simultaneously and automatically with the normal application of the cap.

The invention serves still a further purpose in that the plug or stopper is of resilient material relative to the cap and serves to equalize irregularities in the bottle neck which would otherwise result in a loss of fluid due to inadequate fit of the cap. If the bottle neck is irregular, the cap will not seat properly, and the fluid may leak through the threads of the cap. The plug, as will be hereinafter described, automatically com-

2

pensates or corrects most of such irregularities so that the cap may seat itself in effective sealing position.

The invention will be further understood from the following description and drawings in which:

Fig. 1 is an exploded, cross-sectional view of a cap and plug, the two elements which comprise the instant invention, the same being shown as applied to a bottle neck.

Fig. 2 is a cross-sectional view illustrating the assembled article in use.

The bottle cap 10 is fabricated of a rigid material, whether it be of the plastic type such as "Bakelite," or metal. It is formed with internal threads 14 for the usual purpose of engaging corresponding threads 12 of the bottle neck 13. Depending downwardly from the ceiling of the hollow cap 10 is a projection 14 which may be formed with a lip 15.

The plug or stopper 16 is fabricated of a resilient plastic material. For example, it has been found that polyethylene or polythene is a very satisfactory material for this purpose. This material can be fabricated so as to be resilient and is largely inert and non-absorbent so as not to be affected by any liquid in the bottle B.

Plug 16 is substantially hollow, and an interior cone-shaped spring member 17 is formed therein. The apex of the cone terminates just short of the leading end 18 of the plug. The leading end 18 may be bevelled inwardly so as to facilitate insertion thereof in the neck of the bottle, but in any event, the diameter of the leading end will be approximately the same as the inner diameter of the bottle neck 13 where such leading end normally seats. Obviously, a more effective sealing contact will be provided by the upper portion 19 of the barrel of the plug 16. The cone spring member 17 exerts an outward thrust because the tapering internal wall of the neck 13 attempts to compress the barrel of the plug. Cone 17, being circular, is effective in all directions in producing the required sealing function as was described in my previous application. Thus, it effectively

urges the barrel of the plug radially outward in all directions so as to provide a very satisfactory seal.

Plug 16 is formed with a shoulder 20 and a central recess 21 for receiving projection 14 when the plug and cap are assembled. Assembly may be effected by any convenient operation which will be evident, but a satisfactory method is to first insert the plug into the neck of bottle B and then apply the cap 10 thereover simultaneously screwing it upon the thread 12. It will be ob-

served in Fig. 1 that cap 10 is formed with male threads 22 which may in actual practice comprise two semi-circular half threads slightly spaced from each other. When the plug 16 is inserted into the neck of the bottle, the cap 10 is applied thereover so that the lip 15 enters recess 21 and forms an annular engaging depression in the shoulder 20 as illustrated in Fig. 2. As the cap 10 is rotated so as to engage threads 11 and 12, the threads 22 simultaneously are forced into the shoulder 20 so as to effect a further engagement or anchoring action. As a result, the very act of applying the cap to the bottle neck serves to permanently secure the plug thereto. The pitch of threads 22 are preferably, but not necessarily, the same as that of the threads 11 and 12.

It will be evident from the foregoing that when the user of the perfume or other fluid applies the cap after having extracted a desired amount of perfume, she automatically seals the bottle with the plug 16. Equally, or probably more important, than this advantage is the fact that the plug provides an anchoring effect for the cap, not only during transit but throughout the use of the perfume. This anchoring effect is evident when one commences unscrewing the cap 10. It will be found that during the initial unscrewing, the cap appears to be held to the bottle neck, whereas near the termination of such unscrewing, a distinct loosening effect is felt. This is due to the relative release of anchoring action of the plug 16 as it is withdrawn from the neck of the bottle. The bottle illustrated has a tapering internal neck wall, but the stopper does not require this specific construction. For example, many necks have a top inner bead or lip which will produce a slight constriction of the plug and a consequent pronounced anchoring effect.

Inasmuch as the necks of some bottles, due to various manufacturing processes, are irregular, the ordinary cap sometimes forms a loose fit therewith that subsequently causes leakage of the fluid contained in the bottle. However, by virtue of the instant device, this defect is corrected because the plug, being resilient, automatically assumes a proper seat relative to cap 16 so as to substantially equalize any irregularities. In other words, the plug 16 may tilt slightly pursuant to such irregularities so that the cap 10 will nevertheless provide a secure fit upon the bottle neck 13.

Whereas I have described the assembly of the plug 16 and cap 10 as being effected in situ on the bottle neck, it will be evident that these two elements may be assembled in advance and then applied to the bottle neck.

What is claimed is:

1. A bottle sealing device comprising a substantially hollow cap of rigid material, a central projection depending downwardly within said cap, and an internal plug having a central recess engaged by said projection, said plug being of resilient material relative to said cap and being substantially hollow, a top shoulder on

5 said plug and formed around said recess, said projection extending into and centrally of said shoulder and engaging said shoulder, the remaining internal portion of the plug being free of said projection, and internal threads formed in said cap for engaging outer portions of said shoulder, said cap being formed with bottle neck engaging threads, said shoulder engaging threads being of the same pitch as said bottle neck engaging threads.

2. A bottle sealing device according to claim 1 and including a spring member within and integral with said plug and urging the inner walls thereof outwardly so as to exert an outward thrust against the inner wall of said plug in response to a compressive action against the outer wall of said plug when said plug is inserted into the mouth of a bottle neck.

3. A bottle sealing device according to claim 2 and wherein said spring member comprises a cone having its rim integrally joined with the inner wall of said plug and its apex extending toward one end of the plug, both said plug and said cone spring member being of resilient plastic material.

4. A bottle sealing device comprising a substantially hollow cap of rigid material, a central projection depending downwardly within said cap, and an internal plug having a central recess engaged by said projection, said plug being of resilient material relative to said cap and being substantially hollow, a top shoulder on said plug and formed around said recess, said projection extending into and centrally of said shoulder and engaging said shoulder, the remaining internal portion of the plug being free of said projection, and internal threads formed in said cap for engaging the outer portion of said shoulder.

JEAN R. L. MARTIN.
